WRENCH

Carl H. Leonard, Wakefield, Nebr., assignor of
one-half to John Ashford, Winnebago, Nebr.

Application February 11, 1937, Serial No. 125,336

2 Claims. (Cl. 81—163)

This invention relates to wrenches and has for an important object the provision of a wrench provided with a looped movable jaw which is actuated under the action of differential threads engaged by a jaw operating member.

Another object of this invention is to provide in a wrench a handle carrying nut member at each end provided with interior threads which are of right and left hand pitch so as to effect a speeding up of the movement of the movable jaw upon rotation of the handle or nut member.

A further object of this invention is to provide a wrench of this character which is exceedingly simple in construction and which can be readily manufactured and which is so constructed that after the initial assembly of the device, the nut member cannot be unthreaded entirely from the tubular handle or rod, thus preventing loss of any of the parts of the wrench.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a detail side elevation of a wrench constructed according to an embodiment of this invention.

Figure 2 is a longitudinal section partly in detail of the wrench.

Figure 3 is a fragmentary sectional view taken on the line 3—3 of Figure 1.

Referring to the drawing, the numeral 10 designates generally an elongated tubular member provided at its rear end with exterior threads 13 which are of a right hand pitch and which extend inwardly from the rear end to a suitable point along the length of the tubular member 10. The forward end of the tubular member 10 is provided with a pair of spaced apart flat arms 11 between which a stationary jaw member 12 engages. The jaw 12 is secured between the spaced arms 11 by means of a headed pin 14 or the like.

The work engaging face of the stationary jaw member 12 is provided with an angular face portion 15 within which a pair of the nut faces are adapted to engage. A movable jaw member, generally designated as 16, is constructed in substantially looped form and is provided with parallel side portions 17 connected together at the outer ends thereof with a curved jaw member 18 provided with a serrated inner face portion 19, confronting the work engaging face portions 15 of the stationary jaw member 12.

A jaw operating rod 20 is slidably mounted within the tubular member 10 and its forward end is connected to the movable jaw member 16, as at 21, the forward end of the operating rod 20 being secured as by welding or the like to a connecting member 20 which connects the parallel arms 17 of the movable jaw member 16 together at their inner or rear ends. This connecting member 21 engages between the parallel arms 11 and is movable for a distance substantially equal to the space between the inner end of the stationary jaw member 15 and the rear ends of the parallel arms 11.

The rear end of the operating member 20 is provided with threads 22 which, in the present instance, are left hand threads and may be of a different pitch than the right hand threads 13 on the tubular member 10 so that when the handle 23, having a nut 24 at its forward end, is threaded up onto the right hand threads 13, the nut 25 carried by the rear end of the handle 23 will unthread from the left hand threads 22 at a rate different from the travel of the nut 24 on the threads 13. In this manner, the movable jaw 16 will have a relatively fast movement toward or away from the stationary jaw 15.

In the use and operation of this wrench, the nut or other article to be threaded or unthreaded is engaged within the movable jaw member 16 whereupon the handle 23 may be turned to the left so as to unthread the nut portion 24 from the right hand threads 13. This rearward movement of the nut member 24 will effect rearward movement of the operating rod 20. Due to the differential and left hand threads 22 on the rod 20, when the handle 23 is turned to the left so as to unthread the nut 24 from the threads 13, the nut member 25 at the rear end of the handle 23 will thread forward on the rod 20. Due to the rearward movement of the handle 23 as the nut 25 moves forwardly on the threads 22, the rod 20 will be moved rearwardly at a more rapid rate than is effected by the pitch of the threads 13 so that the movable jaw 16 will move at a relatively rapid rate and thus engage the work between the stationary jaw 15 and the jaw portion 18 of the movable jaw 16. The work may be released from between the two jaw members 15 and 18 by turning the handle 23 forwardly so as to move the nut member 24 forwardly on the right hand threads 13 and simultaneously unthread the nut member 25 from the left hand threads 22.

It is, of course, understood that various changes and modifications may be made in the 55

details of construction and design of the above specifically described embodiment of this invention without departing from the spirit thereof, such changes and modifications being restricted 5 only by the scope of the following claims.

I claim:—

1. A wrench comprising a tubular member provided with threads at one end thereof, spaced apart parallel arms carried by the other end of 10 the member, a stationary jaw member carried by said arms and disposed therebetween, a movable jaw member disposed forwardly of said stationary jaw member, a pair of parallel arms secured to said movable jaw member and engaging on 15 opposite sides of said stationary jaw member, an operating rod disposed within said tubular member and secured at its forward end to said latter parallel arms, threads carried by the rear end of 20 said operating rod, said latter threads being reversely pitched from said first threads, a hollow handle, a nut member carried by the forward end of said handle threadably engaging

said first named threads, and a nut member carried by the rear end of said handle and threadably engaging said second named threads.

2. A wrench comprising a tubular member provided with threads at one end thereof, spaced 5 apart parallel arms carried by the other end of the member, a stationary jaw member carried by said arms and disposed therebetween, a movable jaw member disposed forwardly of said stationary jaw member, a pair of parallel arms secured 10 to said movable jaw member and engaging on opposite sides of said stationary jaw member, an operating rod disposed within said tubular member and secured at its forward end to said latter parallel arms, threads carried by the rear end 15 of said operating rod, said latter threads being reversely pitched from said first threads, and a hollow handle provided with interior threads engaging said first named threads and a second 20 series of interior threads engaging said second named threads.

CARL H. LEONARD.
